UNITED STATES PATENT OFFICE

JOHN EDWARD THORNTON, OF LONDON, ENGLAND, ASSIGNOR TO JOHN OWDEN O'BRIEN,
OF MANCHESTER, ENGLAND

MULTICOLOR CINEMATOGRAPH AND OTHER FILM AND METHOD OF PRODUCING THE
SAME

Original application filed May 5, 1924, Serial No. 711,251, and in Great Britain May 18, 1923. Divided
and this application filed October 3, 1925. Serial No. 60,346.

I have filed an application for this invention in Great Britain, No. 13,358 of 1923 dated May 18, 1923.

The instant application is a division of application Serial No. 711,251, filed May 5, 1924.

This invention relates to the production of multi-color positive pictures on cinematograph film or other transparent supports in four colors by forming four color-component images upon a single support of double standard width and half standard thickness, with two of the color components upon one half-width and the other two upon the other half-width, the second color being printed over the first by the superimposed class of printing and at a second operation after completion of the first pair of prints, the printed film being subsequently longitudinally severed and the two parts superimposed and cemented together with the four separate printed images assembled and superimposed in one picture area to form a single film of multi-color pictures in four colors.

According to the invention, I simultaneously print two of the component images side by side upon a double-width strip of sensitive film-material from a corresponding double-width negative, and after developing and finishing the first pair, each in a different color, I print a second pair of the component images side by side superimposed upon the first pair, and after developing and finishing each of the two prints of the second pair in its own color, the strip is next longitudinally severed to form two single strips which are then cemented together one upon the other, so that the four-color component images are assembled and superimposed in one picture area and form a single picture of four colors.

It is assumed that suitable negatives or printing cliches have been provided, which may be produced by any of the well known methods of splitting a picture into its color components.

The invention will be described with reference to the accompanying drawings.

Fig. 1 is a perspective view of the cinematograph film-positive.

Fig. 2 is a diagrammatic section.

Fig. 3 is a transverse section of a double

width support having a layer of colloid applied thereto with dyed images on said colloid layer.

Fig. 4 is a view, similar to Fig. 3, of a double width support after images have been formed in the first colloid layer and a layer of adhesive and a second layer of colloid has been applied over said images.

Fig. 5 is a plan view of the double width film coated with dye after the images on the second layer of colloid have been printed, developed and finished.

Fig. 6 is a transverse section of a double width support bearing the two colloid layers on each of which partial images are formed.

Printing processes

There are various printing processes which can be utilized, either alone or by combination of two or more, and of these the following are of chief interest for the present invention:

(A) Gelatino-silver emulsion, printed, developed, hardened, bleached, and its images dyed afterwards.

(B) Gelatino-silver emulsion having colored pigment or dyes incorporated with the emulsion, the portion of coloring matter not required in the image being removed after development.

(C) Bichromated gelatine or other suitable colloid, printed and hardened, developed, bleached, washed, and dyed afterwards.

(D) Bichromated gelatine or other suitable colloid having colored pigment or dyes incorporated with the colloid, the portion of coloring matter not required in the image being removed after development.

The second pair of images may also be printed by any of the imbibition processes, such as hydrotype, pinatype, dye-printing, and the like, or by any of the photo-mechanical processes.

The methods of printing, development, and other treatment will vary according to the particular sensitizing and printing processes adopted in preparing the film.

Forming the first pair of component images

The first pair of prints are made direct side 100

by side upon the double-width half-thickness strip of sensitized material, as follows:

A double-width support C of celluloid, cellulose-acetate, or the like, is first prepared with an adhesive substratum A of the usual kind, and then coated with the first layer of gelatino-silver-bromide emulsion F. It is subsequently printed from a double-width negative having thereon the first two of the four component images each of which represents a portion of the completed picture. The printed images are developed, fixed, washed and dried in the usual known manner.

The first pair of images will consist of black deposits of metallic silver, and at this stage several variations of the next step are possible.

By my method this first pair of images is changed from black to colored by first treating in a bath which bleaches the silver and also deposits a metallic mordant upon the silver images. Various suitable baths are well-known, but a bath containing salts of copper or salts of tin is preferred. The first pair of images is then dyed to their respective colors by suitable dyes which will be precipitated upon the mordanted images and thus produce insoluble lakes of each color, while the remainder of the film remains uncolored.

A second adhesive substratum A' is placed upon the dyed images and a further layer of sensitized colloid S is affixed to the adhesive substratum A'. A second pair of non-relief images is then printed side by side upon the layer of colloid S superimposed upon the images of the colloid layer F. The two images of the colloid layer S are then dyed in two different colors to form a four-color picture.

Miscellaneous points

Printing apparatus.—No special description of the printing appliances for photochemical printing is necessary, other than to say that where silver sensitizing is used the film may be printed either by contact or projection, and with printing machines and electric filament lamps as usual.

Double or single width.—In carrying the invention into practice, the use of double-width printing-cliches and double-width positive-strips is described, and I prefer to use a double-width support and make two prints side-by-side as two parallel stripes, in order to ensure that expansion and contraction will be identical for each.

Assembling, cementing and completing

Having completed the two half-pictures positives, upon a double-width thin support which has been cut into two strips after printing and treating, it now only remains to assemble and unite them to form a single positive film.

At this stage it is possible to produce finished positive-films of different characteristics, according to the manner of assembly of the components.

The particular methods of cementing the two sections together are not material to the present invention, for the strips may be joined by any known means capable of making a flexible and permanent union.

But in practice I prefer to unite the films face-to-face (printed-colloid to printed-colloid) by an adhesive A². By this means the delicate printed images are enclosed within the body of the completed film, and the thin celluloid supports form transparent outer covers, the whole forming a scratchless-image multi-color film.

The colors obtainable

Although the result is referred to as a four-color film, (because there are four different-colored component images contained therein) the actual range of colors shown when the picture is projected upon a screen or examined as a transparency is greater than four colors. For example, each finished film-print composed of two thin films of half pictures will contain four primary images, the colors of which may be (as a suitable combination) crimson, green, blue and yellow; and where two or more of these colors are combined in the transparency by portions of the images overlapping, they will form at those points secondary colors comprising orange, blue-green, purple, brown, black, and other intermediate shades; thus the color-scale obtained by this four-color film construction is very much longer in its range than that produced by any two-color or three-color cinematograph film construction such as hitherto known.

Other applications

Although the primary object of this invention is the cheap production of large quantities of cinematograph positive film pictures or similar transparencies of small size in continuous lengths, exactly the same novel construction (utilizing four component-images, combined to produce two half-pictures, each of two colors upon two supports) can be applied to the production of non-cinematograph or non-series transparencies of larger size and various shapes, such as portraits, landscapes, advertisements, or the numerous types of pictures produced by amateur and professional photographers; and it provides a simpler and better system for producing such pictures than many of the other previously-known methods. The process of production is the same for all these applications.

The construction and methods of manufacture are also the same if the invention is applied to other supports, such as rigid glass plates for lantern slides, window transparen-

5 cies, or the like; or to thick stiff flat films; or to thin rollable films; or to films of still thinner and very tenuous description, such as tissues capable of being readily transferred to glass, celluloid or like transparent mediums, and to wood, metal, and like opaque mediums. For all these supports it is desirable to only cement the images face-to-face.

10 What I claim as my invention and desire to protect by Letters Patent is:—

15 1. A four color picture positive cinematograph film comprising two half standard thickness supports cemented together face to face, a layer of colloid upon one support having partial images printed thereon in one color, a layer of adhesive upon said layer of colloid, a second layer of colloid upon the said layer of adhesive and having partial images printed thereon in a second color, a layer of 20 sensitized colloid upon the second support having partial images printed thereon in a third color, a layer of adhesive on the last-named layer of colloid, a second layer of colloid upon the last-named layer of adhesive 25 and having partial images printed thereon in a fourth color, each of the partial images in the four layers of colloid representing those portions of the picture which appear in its respective color.

30 2. The herein-described method of producing a four color single width film transparency consisting in placing upon each half width of a double width semi-thickness transparent support a sensitized colloid layer 35 printing and developing separate partial images of those portions of the picture which appear in two colors, one partial image on each half width, subsequently dyeing said partial images in their respective colors, re- 40 coating the printed and dyed picture area on each half width with a second sensitized colloid layer, printing and developing a further separate partial image of those portions of the picture which appear in two other colors, 45 one partial image on each half width of said support, dyeing the last-named portions of the picture in their respective colors, severing the film into two longitudinal strips, and superimposing the two strips in accurate register and adhesively attaching the two strips 50 with the images borne thereby superposed.

55 3. The herein-described method of producing a four-color single width film transparency consisting in placing a sensitized colloid layer upon each half of a double width semi-thickness transparent support, printing and developing separate partial images of those portions of the picture which appear in two colors, one partial image on each half width, 60 subsequently dyeing said partial images in their respective colors, recoating the printed and dyed picture area on each half width with a second sensitized colloid layer, printing and developing a further separate partial image 65 of those portions of the picture which appear

in two other colors, one partial image on each half width, dyeing the last-named partial images in their respective colors, dampening the colloid faces of both strips and superposing the strips, colloid images to colloid images, in accurate register.

70 In testimony whereof I have hereunto set my hand.

75 JOHN EDWARD THORNTON.
